UNITED STATES PATENT OFFICE.

WILLIAM DERNELL, OF CHICAGO, ILLINOIS, ASSIGNOR TO DERNELL POTATO PRODUCTS CO., OF CHICAGO, ILLINOIS, A CORPORATION OF DELAWARE.

APPARATUS FOR DIPPING VEGETABLES.

1,394,612.

Specification of Letters Patent. Patented Oct. 25, 1921.

Application filed July 28, 1919. Serial No. 313,722.

To all whom it may concern:

Be it known that I, WILLIAM DERNELL, a citizen of the United States, residing in the city of Chicago, county of Cook, and State 5 of Illinois, have invented certain new and useful Improvements in Apparatus for Dipping Vegetables, of which the following is a specification.

My invention relates to an improved apparatus 10 for dipping vegetables and refers more particularly to the dipping of potato chips in heated oil.

The important object of the invention is to furnish a simple, efficient and labor-saving 15 apparatus for lowering vegetables such as potato chips into heated oil, raising them when dipping is completed and providing a means to swing them clear of the dipping kettle so that they can be lowered into a 20 drier, not shown, or removed from the apparatus while it is swung from its position over the heated oil. By using a crossarm with two carriers, one can be dipped while the other is lowered into a drier, not shown, on 25 the opposite side of the supporting column.

In the accompanying drawings:

Figure 1 is a vertical cross sectional view of the apparatus, dotted lines indicating a raised portion of part thereof.

Fig. 2 is a side view of the apparatus shown 30 in Fig. 1, the dotted lines indicating a raised position of the parts.

Referring to the drawings, a metal supporting column 1 with the oven legs 2 are 35 bolted to any suitable table, bench or standard 3. Within the supporting column 1 slides a vertical shaft 4 having a cross-arm 5 with a hook at either end rotatably mounted at its top, while at the bottom of this 40 vertical shaft 4 is fastened a block 6 which moves with the shaft sliding in the slot 7 in the supporting column 1. The vertical shaft 4 is prevented from lateral movement by supporting bearings at the top and 45 middle of the column 1, which allows the shaft to be rotated or raised and lowered in a vertical position only.

A buffer spring 8 is interposed between the lower collar on the cross arm 5 and the 50 top of the supporting column 1. The purpose of this spring is to absorb the shock upon the supporting parts when the carrier is lowered into dipping position or in case the carriers were allowed to drop from a 55 raised to a lowered position.

The cross arm 5 being mounted on the vertical shaft, when the carriers are in a raised position, they may be swung about at will. These carriers 9 may be constructed 60 of any suitable material preferably perforated metal or wire mesh, which allows the oil to drain therefrom. They are supported and held in position by two metallic bands which are bent to form V-shaped legs for the carrier at the bottom and crossed above 65 the carrier where an eye-bolt is secured, furnishing a means by which the carrier may be hooked upon the cross-arm 5. A carrier being hooked on either end of the cross-arm, 70 besides furnishing double action to the apparatus, gives a balancing effect to the cross arm and makes it easier of operation.

To the block 6 is attached the lower end of the lever arm 12, the upper end being fastened to the crank lever 13 near the 75 handle 14. The crank lever 13 is pivoted at 15 in a bearing in the supporting column 1. At the opposite end of the crank lever from the handle at 18 is attached a counter-balance spring 16, which is anchored to the 80 oven standard at 17, and assists in turning crank lever when carriers are to be raised and also assists in preventing them to lower too suddenly in dipping.

In Fig. 2, the apparatus is shown in a 85 raised and lowered position.

By turning the handle 14 in a counter-clockwise manner, from a lowered position, the crank lever assisted by the counterbalance spring 16 which is under tension, pulls 90 up the lever arm 12 which being connected to the vertical shaft 4 raises the shaft together with the cross arm to the dotted line position as shown. The lever arm 12 has a curved portion at its upper end in order that 95 it may clear the pivot bearing 15 when in a raised position. In this position the carriers may swing with the cross arm as they are clear of the dipping receptacle.

A ball bearing 20 is interposed under the 100 cross arm to reduce friction in operation.

I claim as my invention:

1. An apparatus of the class described, the combination with a container for heated liquid, of a carrier for material to be treated 105 therein, a central supporting member, of a shaft slidably fitted in the supporting member, a cross arm rotatably mounted on the shaft to support the carrier, of a lever arm connected to the lower end of the sliding 110

shaft, and a crank lever and counterbalancing spring mechanism connected to the lever arm, whereby the shaft is caused to slide in the supporting member, causing the carrier to be lowered into the liquid and raised therefrom.

2. An apparatus of the class described, the combination with a container for heated liquid, of a detachable carrier for material 10 to be treated therein, a central supporting member, of a shaft slidably fitted in the supporting member, a cross arm arrangement rotatably mounted on the shaft supporting the carrier, of a lever arm connected to the 15 lower end of the shaft and a crank lever fitted with a handle and a counterbalancing spring connected with the lever arm whereby the shaft is caused to slide in the central supporting member causing the cross arm 20 carrier to be raised or lowered.

3. In an apparatus of the character described, the combination with a container for heated liquid, of a carrier for material to be treated, a central supporting shaft 25 member, a shaft slidably mounted therein, an arm rotatably mounted on the shaft to support the carrier, leverage mechanism connected to said sliding shaft, counterbalancing mechanism associated with said leverage 30 mechanism, the arrangement being such that the shaft may be caused to slide in the supporting member and causing the carrier to be lowered into the container and raised therefrom or rotated out of position above 35 the container.

4. In an apparatus for treating vegetables, the combination with a container for heated

liquid, of carriers adapted to be lowered into and raised out of said container, a rotatable supporting member, means for vertically reciprocating the carrier relative to the supporting member and including a supporting arm leverage mechanism and counter-balancing spring members.

5. In an apparatus of the character described, 45 the combination with a container for heated liquid, of duplicate carriers for material to be treated, a central support member having a rotatable slidable shaft mounted therewith, transverse arms attached 50 to said rotatable shaft, leverage mechanism for raising and lowering the carriers into and out of the liquid container, the rotatable shaft being operable to interchange the position of said carriers when in a raised position.

6. In an apparatus for treating vegetables, the combination with a container for heated liquid, of a rotatable cross arm arrangement pivoted on a slidable vertical shaft member 60 operable to lower and raise the carriers in and out of the container and rotatable to interchange the position of the carriers.

7. In an apparatus for treating vegetables, the combination with a container for heated 65 liquid, of receptacles for holding the vegetables carried by cross arms pivoted on a slidable vertical shaft, leverage mechanism for operating said shaft vertically to lower and raise the receptacles in and out of the 70 liquid containers, said receptacles interchangeable with the rotation of the shaft.

WILLIAM DERNELL.
